UNITED STATES PATENT OFFICE

JAMES T. COWLEY, OF LOWELL, MASSACHUSETTS, ASSIGNOR TO THE
LAMSON CONSOLIDATED STORE SERVICE COMPANY, OF NEWARK,
NEW JERSEY.

CONVEYING APPARATUS.

SPECIFICATION forming part of Letters Patent No. 608,577, dated August 9, 1898.

Application filed October 5, 1896. Serial No. 607,822. (No model.)

To all whom it may concern:

Be it known that I, JAMES T. COWLEY, of Lowell, county of Middlesex, and State of Massachusetts, have invented a certain new and useful Improvement in Conveying Apparatus, of which the following is a full, clear, and exact description of the invention, which will enable others skilled in the art to which it appertains to make and use the same.

10 This invention relates to new and useful improvements in conveying apparatus; and the object is to provide means for conveying cash or parcels from one point to another.

15 My invention consists of certain novel features hereinafter described, and particularly pointed out in the claims.

20 In the accompanying drawings, which illustrate a construction embodying my invention, Figure 1 is a diagrammatic view illustrating five stations on a continuous line of a conveying apparatus. Fig. 2 is a side view of the apparatus, taken at the terminal of the line from which the carriers are sent and to which they return and showing the beginning 25 and the ending of track *f*. Fig. 3 is a side view of a portion of Fig. 2, showing the elevator and the carrier thereon. Fig. 4 is a sectional plan view taken on the line *x x*, Fig. 2. Fig. 5 is a side elevation of one of 30 the intermediate stations on the line, showing the elevator in the lower position with the carrier removed. Fig. 6 is a side elevation of Fig. 5 and showing a carrier on the elevator-track section in its lowest position.

35 Fig. 7 is a sectional plan view taken on the line *x' x'*, Fig. 5. Fig. 8 is an inverted plan view of the top plate supporting the stations. Fig. 9 is an enlarged detail view of the elevator and elevator-track section. Fig. 10 is a 40 left-hand end view of the same. Fig. 11 is a part plan view of the elevator, showing the elevator-track in section. Fig. 12 is a detail plan view of the carrier-stopping mechanism on the elevator-track section. Fig. 13 is a 45 right-hand end view of the same. Fig. 14 is a side view of the carrier with the basket omitted. Fig. 15 is a right-hand end view of the same. Fig. 16 is a plan view of the top of the carrier. Fig. 17 is a detail view of the 50 carrier adjustable stop mechanism. Fig. 18

is a rear view of the safety back-stop used on a track as the carrier approaches the station, showing the back-stop in position to stop all the carriers. Fig. 19 is a rear view of the back-stop used at the stations, showing the 55 back-stop in position to allow free passage for all the carriers. Fig. 20 is a rear view of the back-stop, showing the stop in position to engage with a carrier intended for the station at which the back-stop is located. Fig. 21 60 is a rear view of the elevator-track section used at the terminal of the line. Fig. 22 is a plan view, partly in section, of the elevator-track section used at the intermediate stations along the line. 65

Like letters of reference refer to like parts throughout the several views.

Referring to Figs. 2, 3, 4, and 8, *a* represents elevator-rods suspended from the ceiling or other suitable support by means of the 70 top plate *b*. The lower ends of these rods are fastened together by a suitable cross-bar *a*². This cross-bar is provided with lugs *a*³ and set-screws *a*⁴ to receive and hold brace-rods *a*¹ at their lower ends. These brace-rods 75 *a*¹ pass upwardly through the projecting arms *a*⁵ and into suitable supports on the top plate *b*, to which they are firmly secured. Secured to these elevator-rods *a* are suitable brackets *E*, to which the forward and return track *f* is 80 secured, and upon the rods *a* the elevator *K* is mounted and is adapted to slide freely up and down on the rods *a* and adapted to be raised and lowered by the rope *c*, to one end of which is fastened a handle *c*². This rope 85 passes from the handle upwardly over the pulley *b*³ and inwardly over the pulley *b*² (see Fig. 8) and downwardly around a pulley *K'*, mounted in the elevator *K*. The rope then passes upwardly and is secured to the pulley 90 *b'* at the terminal station, but at the intermediate stations the rope passes over this pulley *b'* and downwardly again to the hinged track-section *g* and is secured thereto at *c'*. (See Figs. 5, 6, and 7.) Secured to this top 95 plate *b* is a suitable governor *b*⁶, adapted to regulate the lowering of the elevator. This governor *b*⁶ is connected with the elevator *K* by a cord *d*, one end of which is secured to the elevator at *n*, Figs. 4, 6, and 9. This 100

rope d passes upwardly over the pulley b^4 , around the governor b^6 , back over the pulley b^5 , downwardly and around the pulley n^1 , mounted in the cross-bar a^2 , secured to the 5 bottom of the elevator-rod a . The rope d extends upwardly again and the opposite end is secured to one end of the spring n^2 , Figs. 6 and 9. The opposite end of this spring is secured to the lug n on the elevator-frame K . 10 By this means the governor is revolved as the elevator is raised and lowered. The elevator-rod a are provided with cushion-springs n^3 near their lower ends above the cross-bar a^2 , and upon said springs the elevator K rests 15 when in its lowest position and by means of which the elevator is cushioned as it reaches its lowest position.

In Fig. 2 the outgoing track is shown at a 20 higher elevation than the incoming track, and the carriers depart from the upper track to the various stations and are received on the lower track from said stations. Owing to the incline of said track from its starting to its ending at the terminal station the carriers 25 move along the line by gravity. Where the lines pass the intermediate stations the tracks leading into and passing out from the intermediate stations will be substantially on a level, but with sufficient incline to allow the 30 carriers to move by gravity over the line, as shown in Fig. 5.

Referring now to the terminal station, (shown in Fig. 2,) supposing a carrier is located on the elevator K and is down at the bottom of 35 the elevator-rod a and it is desired to forward the same over the line to one of the other stations the elevator K is raised by pulling on the handle c^2 , attached to the cord c , until the elevator-track section K^2 is in 40 alinement with the upper track f , and the lug l^0 on the elevator-track section (see Figs. 4 and 21) will catch over the end of the lever l , mounted on the bracket E , and retain the elevator in a raised position until the carrier 45 has passed off from the elevator-track section onto the track f . While the elevator is on the elevator-track section and the elevator is in its lower position, the carrier is retained on the elevator-track section by the safety- 50 catch K^{10} . (See Figs. 21 and 22.) The end of this catch projects from the slot K^{23} in the elevator-track section in position to be engaged by the carrier when the catch is in its outward position, and this catch prevents the 55 carrier from passing off from the elevator-track section until the catch is withdrawn in the slot K^{23} .

When the elevator K is raised to the upper track, as before described, the curved portion 60 K^{20} of the catch K^{10} , pivoted to the elevator-frame at K^{18} , engages with the projection K^{21} , mounted on the bracket E , as shown in Fig. 22, and as the elevator is raised the end of the catch K^{10} is gradually withdrawn in the 65 slot K^{23} and out of contact with the carrier, so that the carrier is free to travel off from the elevator-track section onto the main

track f and travel by gravity over the line. As the carrier m passes along the track f after leaving the elevator-track section before 70 described it will strike the end of the finger l^0 , pivoted at l^5 to the bracket l^6 , secured by screws l^7 to the track f . (See Fig. 4.) To this finger l^0 is secured a connecting-rod l^8 , and the opposite end of this connecting-rod is secured 75 at l^2 to the lever l , pivoted at l^1 to the bracket E .

When the carrier engages with the lever l^0 in its travel over the track f , the lever l^0 will be moved forward against the tension of the spring l^{10} and, through the connection 80 before described of the connecting-rod l^8 and lever l , the lever l will be moved out of contact with the lug l^0 upon the elevator-track section and the elevator-track section will be allowed to descend to alinement with the 85 lower track f and the carrier will pass onward by gravity over the line f toward the station to which it was sent.

The carrier m is provided with the usual 90 wheels m^4 and is also provided with lower wheels m^2 to retain the carrier on the track.

The basket is pivotally secured to the carrier at m^3 by a plate m^4 and a cap m^5 , adapted to clamp the bails m^6 of the carrier-receptacle m^7 . The carrier is provided with a plate m^8 , and through the frame of the carrier m and also through the plate m^8 a shaft m^{11} passes. This shaft is provided with a knurled knob m^{12} . This knob m^{12} is provided with an indicator m^{18} , as shown in Fig. 14, and upon 100 the body of the carrier-frame m is an index m^{19} . This index is figured to correspond with the number of stations on the line. The opposite end of this shaft m^{11} is reduced in size at m^{11} , and upon the extreme end is mounted 105 the plate m^{16} , provided with pins m^{17} and m^{20} . (See Figs. 15 and 17.) Upon the reduced portion m^{11} of this shaft m^{11} is loosely mounted the washers m^{15} and spring m^{20} . The pin m^{20} is adapted to enter into the holes m^{21} in the 110 plate m^8 on the carrier m . One of these holes m^{21} is provided for each different graduation.

When it is desired to change the graduation of the carrier so that the carrier may be sent to any desired station on the line, the knob 115 m^{12} , mounted on the shaft m^{11} and provided with the indicator m^{18} , is pushed in against the tension of the spring m^{20} . This moves the plate m^{16} away from the plate m^8 and carries with it the pin m^{20} out of the holes 120 m^{21} in the plate m^8 , and the knob m^{12} may then be rotated until the indicator m^{18} will point to any figure on the index that may be desired, and when the knob m^{12} is released the spring m^{20} will move the shaft m^{11} back 125 to its original position and the pin m^{20} will enter another hole m^{21} in the plate m^8 corresponding with the figure on the index, and the position of the pin m^{20} will thus be changed to correspond with the graduation on the index 130 to which the indicator m^{18} has been moved.

Referring now to the station to which the carrier has been forwarded over the track f , as the carrier m approaches a station should

the elevator K not be in alinement with the track and in position to receive the carrier there is provided a back-stop to arrest the carrier and retain it until the elevator is raised into alinement with the track. This back-stop is shown in Figs. 4, 7, 18, 19, and 20 and is constructed as follows:

Pivoted at E³ in the lugs E² on the bracket E is a bell-crank lever E', one end projecting outwardly to engage with the elevator-track section and the opposite end extending upwardly and having an eye E¹², in which is mounted one end of the rod E⁴. The opposite end of this rod is secured to a lever E⁵, mounted in the lug E⁶, secured to the track f. This lever E⁵ has a rod E⁷, extending at right angles to the portion E⁵, around which is a coil-spring E¹⁴. Upon the end of the rod is mounted the slide E¹¹, which moves freely thereon and is held in an upright position and is guided by the U-shaped guide E¹³, which is firmly secured to the rod E⁷ by a suitable set-screw. Upon the extreme end of the rod E⁷ is a guide-block E⁸, which is adapted to move freely in the slot E⁹ in the bracket E¹⁰, secured to the track f. Secured to the outer end of this bracket E¹⁰ at E¹⁶ is a spring E¹⁵, and the opposite end is secured at E¹⁷ to the lever E⁵. The object of this spring is to move the rod E⁷, carrying the slide E¹¹, in toward the track f.

When the slide E¹¹ is in the position shown in Fig. 18, a carrier passing over the track f will be arrested by the pin m¹⁷ on the carrier striking the slide E¹¹ and the spring E¹⁴ will yield and act as a cushion to gradually check the speed of the carrier.

When the elevator-track section K² is raised up to alinement with the tracks f, as in Fig. 19, the lug K³⁵ on the end of the elevator-track section K² will be pushed backward against the tension of the spring K¹², (shown in Figs. 11, 21, and 22,) so that the lug K³⁵ will pass over the end of the lever E', and when allowed to settle down to its normal position, as shown in Fig. 19, the slide E¹¹, through the connections of the rod E⁷, lever E⁵, rod E⁴, and lever E', will be moved out of the path of the carrier to the position shown in Fig. 19 and the carrier will be allowed to pass onto the elevator-track section.

The elevator-track section is constructed as follows: Secured to the elevator K is a short section of track K², provided with a groove in which the slide K³ freely moves. (See Figs. 9, 10, 11, and 13.) Upon one end of this slide and upon the stud K¹⁶ is mounted the safety-catch K¹⁴, provided with stop-pins K¹⁵ above and below. This catch is intended to prevent the rebounding of the carrier when arrested on the elevator. Passing through the slot K⁹ in the elevator-track section is a lug K⁴, firmly secured to the slide K³ by the screws K³³. Within this lug is mounted the lever K⁵, provided with the spring K⁶ and the pin K⁷, mounted in the upwardly-extending portion K⁸. Passing through a hole K¹⁰ in the

lug K⁴ is a rod K¹¹, one end of which is secured to the lug K³⁵ on the end of the slide K³, working in the slot K³⁶, and the other end moves freely in the lug K¹³, firmly secured to the elevator-track section. Around this rod is a spring K¹², adapted to be compressed as the slide carrying the lug K⁴ is moved downward by the momentum of the carrier. Upon one end of the elevator-track section is mounted a lug K²⁵, carrying the dog K²⁶, one end of which projects through a slot K³² in the elevator-track section and is adapted to be engaged by the beveled end K³¹ of the slide K³ and pushed back by the same as the slide is moved backward. This dog is also provided with a finger K²⁸, adapted to rest on the pin K³⁰ on the bracket E and support the elevator-track section in alinement with the track f when the parts are in position shown in Fig. 11. This dog is provided with a spring K²¹, one end of which is fastened to the dog at K²⁹ and the other end is fastened at K²² to the catch K¹⁹, before described.

By reference to Figs. 6 and 7 it will be noticed that a hinged track-section g has been provided to drop down and fill the space caused by the elevator-track section lowering down with a carrier, and thus forms a continuous line of track f, so that the carriers passing to stations beyond will not be delayed. This is constructed of a short section of track g, Figs. 6 and 7, which is provided with brackets g', pivoted at g² to the bracket E. To this track-section is secured one end of the cord c at c', and when the elevator is raised by the operator pulling on the handle c², attached to the cord c, the track-section is raised to the position shown in dotted lines in Fig. 6, and when the elevator is raised to alinement with the track f the curved guard S on the elevator K will engage with the track-section g and hold it in a raised position out of the path of a carrier passing along the track or onto the elevator.

Now when a carrier arrives at a station to which it was sent and has passed onto the elevator the pin m¹⁷ on the carrier engages with the pin K⁷ on the elevator, as before described, and the carrier is arrested. The momentum of the carrier will move the slide to which the lug carrying the pin K⁷ is connected backward, carrying with it the rod K¹¹ and the lug K³⁵ off of the end of the lever E'. The opposite end of the slide will move the end K²⁸ of the dog K²⁶ off of the pin K³⁰, and the elevator will be free to descend, and as it drops the track-section g will drop down and fill the space caused by the descending elevator. This track-section is also adapted to rest on the lever E' and operate the back-stop, before referred to, to release any carrier that may have been arrested.

It will be noticed that any number of carriers can be sent to a single station. Now should a carrier be on the elevator and the elevator be lowered the other carriers are free to pass along the line; but if another carrier

should be sent to that station some means must be provided to arrest that particular carrier at the station until the elevator is raised to receive it. To accomplish this, I provide the slide E¹¹ on the back-stop with the pin E¹⁸. (See Fig. 20.) Those pins are graduated the same as the pins K⁷ on the elevator-track section. Now when the track-section g drops down to alignment with the track f the slide E¹¹ is moved out only to the position shown in Fig. 20, and not out to the extreme distance, as shown in Fig. 19, when engaged by the elevator-track section. This partial movement of the slide E¹¹ leaves the pin E¹⁸ in position to engage with the pin m¹⁷ on the carrier and arrest that particular carrier, but allows all others to pass freely along the track; but when the elevator-track section is raised the slide E¹¹ is moved out fully, as shown in Fig. 19, and the carrier will pass onto the elevator, as before described. The pins K⁷, mounted in the upright portion K⁸ of the lever K⁵, secured to the slide K³, are vertically arranged for each elevator-track section K² to correspond with the positions of the pins m¹⁷, so that when the pin m¹⁷ has, for instance, been set for station No. 1 the pin K⁷ on the elevator-track section at station No. 1 will be in such position as to engage with the pins m¹⁷ to stop the carrier; but the pins m¹⁷ on the other carriers, set for other stations, will not be stopped by the pin K⁷ at station No. 1. In other words, the pins K⁷ at each station are located to correspond with the adjustments of the pins m¹⁷. After the elevator is lowered within reach of the operator before it can be forwarded over the line again the carrier must be moved past the pin K⁷. In order to do this, the operator pulls down on the arm K³⁷ of the lever K⁵ and the pin K⁷ is swung out of the path of the carrier, which then moves forward sufficiently so that the stop-pin on the carrier will be on the opposite side of the pin K⁷. When the operator releases the arm K³⁷, the spring K⁶ will return the lever to its original position. On the arm K³⁷ the rod K³⁸ is mounted and projects downwardly within reach of the operator, thus providing a convenient means for operating the lever K⁵. I do not limit myself to the arrangement and construction shown, as the same may be varied without departing from the spirit of my invention.

Having thus ascertained the nature of my invention, what I claim as new, and desire to secure by Letters Patent of the United States, is—

1. In a conveying apparatus, a track, a carrier adapted to travel on said track, a series of elevators each having a track-section adapted to be brought into alignment with said track, stopping mechanism located at relatively different points on the several ele-

vator-track sections, and stopping mechanism on the carrier adapted to be adjusted to engage with any one of said stopping mechanisms on the said elevator-track sections. 65

2. In a conveying apparatus, a track, a carrier adapted to travel on said track, a series of elevators each having a track-section adapted to be brought into alignment with said track, means for holding the elevator-track section in alignment with said track and adapted to be released by the carrier passing onto the elevator-track section, stopping mechanism located at relatively different points on the several elevator-track sections, and stopping mechanism on each carrier adapted to be adjusted to engage with any one of said stopping mechanisms on said elevator-track sections. 70 80

3. In a conveying apparatus, a track having a removable-track section normally in line with said track, a carrier adapted to travel on said track, a series of elevators each having a track-section adapted to be brought into alignment with said track, means for holding the elevator-track section in alignment with said track and adapted to be released by the carrier passing onto the elevator-track section, stopping mechanism located at a different point on each elevator-track section, stopping mechanism on each carrier adapted to be adjusted to engage with any of said stopping mechanisms on said elevator-track sections, and a graduated back-stop adapted when said removable-track section is in alignment with said track to allow the passage of carriers belonging to stations beyond and to stop the carrier intended for the station at which said back-stop is located. 90 95

4. In a conveying apparatus, a track having a removable-track section normally in line with said track, a carrier adapted to travel on said track, a series of elevators each having a track-section adapted to be brought into alignment with said track, means for removing said removable-track section from alignment with said track to permit the alignment of said elevator-track section with said track, and a graduated back-stop adapted when said removable-track section is in alignment with said track to allow the passage of carriers belonging to stations beyond and to stop the carrier intended for the station at which said back-stop is located. 105 110 115

In testimony whereof I have signed my name to this specification, in the presence of two subscribing witnesses, on this 18th day of July, 1896.

JAMES T. COWLEY.
